UNITED STATES PATENT OFFICE.

EUGENE ROBERTS, OF SALT LAKE CITY, UTAH, ASSIGNOR TO THE WESTERN STATES MACHINE COMPANY, OF SALT LAKE CITY, UTAH, A CORPORATION OF UTAH.

SCREEN FOR CENTRIFUGAL BASKETS.

Application filed August 18, 1921. Serial No. 493,324.

The present invention deals with the problem of maintenance of the perforated screens or linings of centrifugal separators used in the separation or extraction of the liquid content from the solid matter as exemplified in the art of manufacturing or refining sugar or similar moisture-containing materials.

As the perforated sugar centrifugal basket is rotated usually at a surface speed of more than 2 miles a minute the pressure of the solid sugar against the perforated lining is exceedingly heavy particularly near the bottom of the basket where there is the greatest accumulation of the massed sugar. This excessive pressure greatly increasing toward the bottom of the basket results in an actual stretching of the screen which is greatest near the bottom, thereby tending to give the screen a slight thrust roll conical form with the greatest diameter at the base. As the screen is externally supported by the cylindrical basket wall and the interposed or intermediate reticulated backing, such stretching tends to cause the screen to buckle or wrinkle so that injury is caused when the sugar-discharging plow is brought into working contact with the interior face of the perforated screen as the basket is rotated in the operation of removing the walled-up sugar.

The prevention of such buckling or wrinkling producing unevenness in the screen and leading to rapid deterioration of these expensive parts is the object of the present invention. In my former Patent 1,300,486, dated April 15, 1919 there was disclosed a form of joint for centrifugal basket screens intended to prevent the spreading apart or separating of the overlapped ends of a centrifugal basket screen, but while this joint accomplishes its purpose of keeping the overlapped edges of the screen close together, it does not prevent the stretching of the screen under the outward pressure of the sugar mass whereby the screen is gradually caused to assume the thrust roll conical shape which prevents it from properly fitting the intermediate of the cylindrical basket wall which leads to buckling and unevenness in the screen.

The present improvement consists essentially in making the perforated basket lining or screen in a plurality of separate sections having their overlapped end edges

joined together by an expandible joint from top to bottom whereby both the upper and the lower portions of the screens may stretch equally but without buckling or formation of ridges or wrinkles in the screen itself in order that the screen may be self-adjusting no matter how great the internal pressure so that it will always preserve the cylindrical form and thus lie smoothly against the interior of the cylindrical basket wall of the interposed reticulated backing.

In the accompanying drawings I have illustrated a form of construction embodying the principles of this invention in which:

Figure 1 is a perspective view showing the multi-part screen inside the perforated basket, the front portion of the basket of the reticulated lining being broken away to show the front half of the screen.

Figure 2 is a flat development showing two sections of the screen united together by a lap joint such as illustrated in my aforesaid Letters Patent.

Figure 3 is a detail of the screen in cross section on the horizontal plane intersecting the external series of overlapping tongues.

In the practice of this invention, according to the form illustrated in the drawings, I employ a sheet metal screen perforated in accordance with the usual practice and made up as shown in this case of three sections 4, each of which is provided along one vertical or end edge with a series of properly spaced vertical slots 5. The cooperating or matching adjacent end edge of the next screen section is slotted circumferentially for a few inches to form a series of tongues 6 narrow enough to be thrust through the slots 5 from the inside, leaving their ends protruding outside and beyond the slotted portion of the adjacent section.

Every alternate tongue 7, which is formed by a circumferentially slotted end edge of a screen section, is passed directly outside of the end edge of the adjacent section having the vertical slots 5 so that the two series of tongues form an overlapping interwoven or jointed structure with a series of external tongues passing entirely outside of the overlapped portion of the next section and a series of inserted tongues pass from the inside out through the slots 5 and overlapping the exterior of the next section.

The screen when thus assembled is in-

serted inside the usual cylindrical basket 1 which is provided with the reenforcing ribs 2, and which also carries an interior reticulated backing 3 to allow the flow of liquid 5 escaping through the screen sections 4 to the perforations in the basket which are larger and more widely separated than the perforations in the screen which latter are indicated at 8, and which extend through- 10 out the screen sections inside of their edges but for convenience are shown only in part.

The screen having been assembled and inserted inside the basket and backing can then be expanded by hand until its fits perfectly 15 against the surrounding retaining wall formed by the basket or by the backing.

The rapid rotation of the centrifugal basket with its interior mass or sugar tends to expand the lining but has the expansible 20 joints located at intervals around the screen extended from top to bottom. The screen is thus made self-adjusting and is always free under such pressure to seat itself snugly against its surrounding supporting wall and 25 thereby maintain its proper cylindrical form without fold or wrinkle against which the discharger plow may impinge to the manifest injury of the screen. Any desired 30 number of joints of this type may be used in the screen, but the three joints illustrated in the drawings are sufficient to effectively accomplish the desired purpose and greatly

prolong the life of the screen while avoiding also injury to the plow tip as well.

What I claim is:

1. A screen for a centrifugal basket embracing in construction a plurality of circumferential sections having their opposite ends overlapping the adjacent ends of the next section and joined therewith to prevent lateral separation while allowing circumferential expansion, substantially as described. 40

2. A screen for a centrifugal basket embracing a series of arcuate sections whose adjacent end edges are provided with a co-operating series of tongues and slots to form interwoven overlapping joints, whereby the arcuate sections may be joined to form a complete cylindrical screen capable of expanding 45 equally at top and bottom so as to preserve its cylindrical form when expanded under the pressure of the interior mass of solid material, substantially as described. 50

3. A screen for centrifugal baskets embracing a plurality of arcuate sections whose adjacent ends are joined together by circumferentially extensible overlapping joints extending from top to bottom of the screen, 55 substantially as described. 60

In witness whereof, I have subscribed the above specification.

EUGENE ROBERTS.
